US00D947430S

(12) **United States Design Patent** (10) **Patent No.:** **US D947,430 S**
(45) **Date of Patent:** **** Mar. 29, 2022**

(54) **LANTERN**

(71) Applicant: **Liuning Wu**, Ningbo (CN)

(72) Inventor: **Liuning Wu**, Ningbo (CN)

(73) Assignee: **Ningbo Worth International Trade Co. Ltd.**, Ningbo (CN)

(**) Term: **15 Years**

(21) Appl. No.: **29/738,441**

(22) Filed: **Jun. 17, 2020**

(51) LOC (13) Cl. **26-02**

(52) U.S. Cl.

USPC **D26/37**; D26/40; D26/41

(58) **Field of Classification Search**

(57) **CLAIM**

The ornamental design for a lantern, as shown and described.

DESCRIPTION

FIG. 1 is a top front perspective view of the lantern, showing my new design;

FIG. 2 is a bottom rear perspective view thereof;

FIG. 3 is a front view thereof;

FIG. 4 is a rear view thereof;

FIG. 5 is a left side view thereof;

FIG. 6 is a right side view thereof;

(Continued)

FIG. 7 is a top view thereof; and,
FIG. 8 is a bottom view of the lantern.
